CLAIM

The ornamental design for a corrugated feed horn antenna, as shown and described.

DESCRIPTION

FIG. 1 is a perspective view of a corrugated feed horn antenna design showing my new design.

FIG. 2 is a front view of a corrugated feed horn antenna.

FIG. 3 is a rear view of a corrugated feed horn antenna.

FIG. 4 is a right side view of a corrugated feed horn antenna.

FIG. 5 is a left side view of a corrugated feed horn antenna.

FIG. 6 is a top view of a corrugated feed horn antenna; and,

FIG. 7 is a bottom view of a corrugated feed horn antenna.

Any shading and cross-hatching are not features of the design but are utilized to illustrate the surface contours of the corrugated feed horn antenna design in the drawings.

The broken lines depict portions of the corrugated feed horn antenna that form no part of the claimed design.
